No. 755,121.

PATENTED MAR. 22, 1904.

F. C. FISHER.

ELECTRICAL APPARATUS FOR THERAPEUTIC PURPOSES.

APPLICATION FILED SEPT. 21, 1903.

NO MODEL.

Fig:1.

UNITED STATES PATENT OFFICE.

FREDERICK COURtenay FISHER, OF BRISTOL, ENGLAND.

ELECTRICAL APPARATUS FOR THERAPEUTIC PURPOSES.

SPECIFICATION forming part of Letters Patent No. 755,121, dated March 22, 1904.

Application filed September 21, 1903. Serial No. 174,075. (No model.)

To all whom it may concern:

Be it known that I, FREDERICK COURtenay FISHER, a subject of the King of Great Britain, and a resident of Bristol, in the county of Gloucester, England, have invented certain new and useful Improvements in Electrical Apparatus for Therapeutic Purposes, (for which I have applied for a patent in Great Britain, No. 13,937, dated June 23, 1903,) of which the following is a full, clear, and exact specification.

This invention relates to improvements in electric apparatus for therapeutic purposes, whereby an electromagnetic and faradic or electromagnetic faradic current may be supplied.

Referring to the annexed drawings, Figure 1 is a plan view of my invention as applied to a belt to be worn on the body, showing the arrangement for the electromagnetic and faradic current; Fig. 2, a plan view of my invention applied to what I term a "pad;" Fig. 3, a side elevation of interrupter; Fig. 4, an end elevation of same.

Referring to Figs. 1 and 2, I place along the belt a number of induction-coils *d*, which are arranged in groups of equal number, each group being carried by one of the sliding pieces *a* sliding on belt *v*, the primary circuits of which (shown by the dot-and-dash lines) are connected up in series and supplied with current from a suitable battery *a'*, carried on the person, the secondary circuits being connected as shown, the following being the path of the current: One end of the secondary circuit-wire *b* is attached to the resistance-plate *c* and passes from thence to the first coil *d*. All the secondary coils are then connected in series, the disks *e* and *f* being the terminals in the secondary circuit *b* and are connected as shown. The resistance-plate *c* aforesaid may be made of any suitable material, such as wood fiber, and consists of the pivoted arm *l*, engaging with the contact-points *m*, so as to vary the resistance. I introduce into the primary circuit an interrupter *w*, as shown in Figs. 3 and 4, which consists of laminated cores *n* and *o*,

which carry the coils *p* and *q*, the armature *r* being pivoted to the arm *s*, attached to the laminated cores, the current passing along the arm *s*, through the armature *r*, to the coils *p* and *q*, the contact being broken at point *t* by the attraction of the armature to the coils. It will thus be seen that secondary currents are rapidly induced in secondary circuit. The belt is worn so that the disks aforesaid are in contact with or annexed to the body, the current passing from the disks *e* to the disks *f* through the body.

Referring to Fig. 2, in this case the coils are conveniently arranged upon a pad *u*, the interrupter and the resistance-plate being provided as in the case of the belt. This pad may be used for various purposes, such as by providing in conjunction therewith a pair of socks which would be connected with the end of the secondary circuit-wires *z*. At the same time the pad is also provided with the handles *y*, so that it may be conveniently handled, and, if desired, the pad may be worn on any convenient part of the body where it is not convenient to use a belt, in which case an electromagnetic effect would be produced upon the wearer.

Having thus described my invention, what I claim, and desire to secure by Letters Patent, is—

In electric apparatus for therapeutic purposes in combination, a series of electric induction-coils, a belt carrying said series of induction-coils, an interrupter also carried by the said belt and inserted in the primary circuit, said interrupter consisting of laminated cores, coils surrounding said laminated cores, a pivoted armature, a fixed arm or lever extending over said pivoted armature, a contact-point carried by said arm and engaging with said armature, springs holding said armature in contact position, the current being broken between the armature and said point when the armature is directed to the coils, aforesaid series of induction-coils being arranged in groups, and all connected in series, the secondary circuit of each group being con-

nected to contact-plates which when the belt is worn are in contact with the body so that the current passes from one contact or pair of contact-plates to another through the body, 5 an adjustable resistance-plate carried by the belt and inserted in the secondary circuit substantially as described herein.

In testimony that I claim the foregoing I have hereunto set my hand this 30th day of July, 1903.

FREDERICK COURtenay FISHER.
Witnesses:

WILLIAM JOHN WEEKS,
RUDOLPH CHARLES NICKOL.
